UNITED STATES PATENT OFFICE.

MATTHEW M. KANE, OF ROME, GEORGIA.

WATER-METER BOX.

1,139,188.

Specification of Letters Patent.

Patented May 11, 1915.

Application filed June 11, 1913. Serial No. 773,084.

To all whom it may concern:

Be it known that I, MATTHEW M. KANE, a citizen of the United States, residing at Rome, in the county of Floyd and State of Georgia, have invented certain new and useful Improvements in Water-Meter Boxes, of which the following is a specification.

This invention relates to water meters and similar devices, and has for one of its objects to improve the construction and increase the efficiency and utility of devices of this character.

Another object of the invention is to provide a simply constructed attachment whereby the "reading" of the meter will be materially facilitated.

With these and other objects in view the invention consists in certain novel features of construction as hereinafter shown and described and then specifically pointed out in the claims, and in the drawings illustrative of the preferred embodiment of the invention.

Figure 1 is a plan view of a water meter box with the improvement applied and in open position. Fig. 2 is a section of the box on the line 2—2 of Fig. 1.

Corresponding and like parts are referred to in the following description and indicated 30 in all the views of the drawings by the same reference characters.

The improved device may be applied to meters of various forms, and it is not desired to limit the invention to any specific 35 form of meter or like device, but for the purpose of illustration the improved device is shown applied to a conventional meter in which 10 represents the casing of the meter with the intake pipe 11 entering at one side 40 and the outlet pipe 12 leading therefrom at the opposite side, these parts being of the usual construction.

The interior construction of the meter does not constitute a part of the present invention and it is not deemed necessary to illustrate the same.

The body 10 of the meter is provided with a closure 13 hingedly united thereto at 14 and serving as a closure to the portion of the 50 casing 10 which engages the indicator mechanism including the dials and the denoting hands or fingers. Inclosing the casing 10 of the meter and likewise inclosing portions of the pipe 11—12, is a protecting casing 15 of any suitable shape, but preferably with rounded ends and a closure 27 with a flat

upper side. The upper edge of the casing 15 is formed with a shoulder to receive the closure 27, and the latter is provided with a plurality of supporting and strengthening 60 brackets 28, as shown.

Formed through the upper side of the casing 15 is an opening 16 provided with a closure 17 which closely fits the opening, and is supported thereon upon a suitable ledge 65 or rabbet surrounding the opening. The upper side of the casing 15 is located some distance above the upper face of the body 10, and the closure 13 opens through the opening 16, consequently, the closure 13 can 70 not be opened so long as the closure 17 is in its lower position.

The upper face of the casing 15 and the closure 16 is roughened to prevent the feet of persons walking thereon from slipping. 75 The casing 15 is firmly embedded in the roadway or walk with its upper face flush with the body of the walk or roadway, hence the necessity for forming the upper face roughened to enable persons to readily walk 80 thereover.

At one end the rabbet of the opening 16 is wider than at the other parts of the opening, and the wider portion is provided with apertures 18 to receive curved projections 85 19 extending from the closure 17. At their lower ends the curved members 19 are laterally widened to bear beneath the lower face of the top of the casing 15. By this means when the closure 17 is in its lower 90 or closed position the curved bars 19 project into the interior of the casing 15, and when the closure 17 is opened the curved members 19 serve as hinges to enable the closure to swing upwardly and rearwardly, 95 the closure being limited in its rearward movement by the lateral projections 20 as illustrated in Fig. 2. Formed in the upper face of the top of the casing 15 at the side of the opening 16 opposite to the wider portion 100 of the rabbet having the slots 18 is a recess or depression 21 while a similar recess or depression 22 is formed in the free end of the closure 17 and registers with the recess 21. Located within the recesses 21 is a button device 23 having a pintle or pin 24 extending downwardly therethrough and into the interior of the casing 15. The pin 24 is provided with a stop nut 25 at its lower end and surrounded by a spring 26 which exerts its force to maintain the button device 23 yieldably in its downward position. The

recess 21 is of sufficient size to enable the button 23 to be turned one-fourth around to remove its free end from the recess 22 and thus release the closure 17. The spring 26 thus exerts its force to maintain the button in engagement with the closure 17 and prevent its accidental displacement while at the same time the button will yield when pressure is applied laterally thereto to release the closure. By this simple means the upper end of the meter casing 10 including its closure 13 is covered and protected, while at the same time the registering dials and indicating fingers are readily accessible for "reading" the state of the meter and without the necessity for removing the cover 27 of the casing 15 or otherwise disturbing the parts. The reading of the meter is thus materially facilitated without interfering with its operation or causing delay.

Having thus described the invention, what is claimed as new is:

1. In a device of the class described, a casing including a horizontal top member provided with apertures each having a reduced lateral offset, a closure for the top, arms extending from the closure and engaging respectively in the reduced offsets of the apertures and provided with lateral

projections bearing beneath the top when the closure is open and in one position and adapted to pass through the apertures to release the closure when the same is in another position.

2. In a device of the class described, a casing including a horizontal top member having an opening with a supporting shoulder surrounding the opening, said top member being provided with apertures through the horizontal portion of the shoulder and each having a reduced lateral offset, a closure for the top member and adapted to engage the shoulder when closed, arms extending from the closure and engaging respectively in the reduced offsets of the apertures and provided with lateral projections bearing beneath the shouldered portion of the top when the closure is open and in one position and adapted to pass through the apertures to release the closure when the same is in another position.

In testimony whereof I affix my signature in presence of two witnesses.

MATTHEW M. KANE. [L.S.]
